GOLFER'S FOOT GUIDE

Lynn H. Clark, Rockford, Mich.

Application November 21, 1952, Serial No. 321,913

2 Claims. (Cl. 273—188)

This invention relates to golfers' foot guides, and more particularly to guides for properly locating and holding the feet of a player while he is swinging the golf club at the ball. 15

It is recognized in the game of golf that a proper stance is essential for good playing. To acquire a good 20 stance the player's feet must be properly placed with relation to each other and with the ball. During the swinging of the club the feet, and especially the balls thereof, must remain firmly in place although the heels may be raised somewhat and swung a trifle to permit the necessary pivoting of the player's body. 25

This invention provides means for adjusting the player's feet properly and firmly holding their forward parts in the proper positions while permitting some swinging movements of the heels for pivoting. The device also automatically and without adjustment, fits various sizes of shoes so that it may be used without change by different people. 30

The invention provides various new and useful features of construction and arrangement as hereafter more fully described and particularly pointed out in the claims, reference being had to the accompanying drawings in which, 35

Fig. 1 is a perspective view of one of the foot guides which are usually used in pairs,

Fig. 2 shows a plan view of a pair of the foot guides with the player's feet shown diagrammatically,

Fig. 3 is a rear elevation of one of the foot guides,

Fig. 4 is a fragmentary sectional elevation showing modifications of construction, and 45

Fig. 5 is another fragmentary sectional elevation showing other modifications of construction.

Like reference numbers refer to like parts in all of the figures.

The base plate 1 is flat and may be rectangular or other suitable shape and is preferably rather heavy so that it will hold its position on the ground. The base plate may be made of steel of suitable thickness for the desired weight. 50

Upon the upper surface of the base plate 1 are located two generally vertical elongated guide strips 2 which are permanently and suitably attached to the base plate 1 as by the flanges 3 which may be welded to the base plate. These guide strips 2 are spaced apart and located divergently from front to rear, their forward portions being spaced apart a distance substantially equal to the width of a smaller sized player's shoe and their mid-portions are spaced the width of a larger shoe. The guide strips 2 are shown in Figs. 1, 2 and 3 as being slightly inclined inwardly from the vertical. 55

In using these foot guides it is preferable to have one for each foot although a single one may be used with

2

some benefit. When two are used they are placed upon the ground in the predetermined proper locations for the individual player who is to use them. The player then steps upon the base plates and thrusts his shoes 4 forward between the guide strips 2 until their forward portions adjacent the balls of the feet are securely wedged between the diverging strips. The ball to be struck is placed in the proper location forward of the guides.

The player is now ready to stroke the ball with the club. 10 The forward portions of his feet being firmly wedged between the in-turned guide strips 2, are securely held in position and cannot move while the club is being swung although, as his body pivots, the heels may be raised and pivoted to some extent.

To aid in holding the base plate from movement on the ground, prongs 5 may be struck downward therefrom or carks 6 may be screw-threaded into the plate and these pierce the ground and keep the plate from moving. The guide strips may be modified in shape such as being vertical as shown at 2^a in Fig. 5, or as having in-turned upper edges as shown at 2^b in Fig. 4.

These foot guides are primarily intended for beginners or those who are inexpert at the game of golf. They will be mostly used for practicing but may be carried and used on the course while playing the game. With them the player may either, of his own accord or by the instruction of a professional, learn the proper position of his feet for a good stance, and with this knowledge he can place the guides upon the ground in position so that when his feet are in them they will be properly located. Then in stroking the ball his feet will be held properly and will not move during the swing but the heels may pivot somewhat to accommodate the body pivot. These are all important for proper golf playing.

The invention is defined in the appended claims which are to be considered comprehensive of all forms coming within their scope.

I claim:

1. A golfer's foot guide for the purpose of locating a foot of a golf player comprising, a substantially flat base plate adapted to lie horizontally upon the ground, said base plate being somewhat longer than a player's shoe and having extending upwardly therefrom two guide strips spaced divergently from each other from front to rear, the space between the guide strips at their mid portions being substantially equal to the width of the sole of the shoe of the player and at the rear the guide strips being spaced a distance greater than the width of the heel of the player's shoe whereby, during the swinging of a golf club, the player's heel may swing laterally a limited distance and the sole may pivot but is held from lateral displacement relative to the base plate and the ground on which it rests. 55

2. The elements of claim 1 in which said guide strips are inclined inwardly toward each other in an upward direction.
